By Henry C. Ward Atty.

UNITED STATES PATENT OFFICE.

CHARLES W. KENNEDY, OF PITTSBURG, PENNSYLVANIA.

DESIGN FOR A STOVE-LID LIFTER.

SPECIFICATION forming part of Design No. 25,764, dated July 7, 1896.

Application filed May 15, 1896. Serial No. 591,715. Term of patent 31 years.

To all whom it may concern:

Be it known that I, CHARLES W. KENNEDY, a citizen of the United States of America, residing at Pittsburg, in the county of Allegheny and State of Pennsylvania, have invented a certain new and useful Design in Stove-Lid Lifters, of which the following is a specification, reference being had therein to the accompanying drawings.

10 This invention relates to certain new and useful designs in stove-lid lifters, of which the following is a specification, reference being had to the accompanying drawings, forming a part thereof.

15 In the drawings, Figure 1 is a perspective view of my stove-lid lifter. Fig. 2 is a side view of the same, these two views being deemed necessary to fully illustrate my design.

20 The leading feature of my design consists

in the forked ends *aa*, which are curved outwardly and then inwardly and slightly tapered, as shown at *bb*. A rivet *c* fastens the two sides of the handle *d* together at the point where same are curved outwardly to form the 25 forked ends, a loop *e* being formed in the other end for convenience in hanging the lifter, and the edges are beveled slightly, as shown throughout the drawings.

Having described my design, what I claim 30 is—

The design for a stove-lid lifter as herein shown and described.

In testimony whereof I affix my signature in presence of two witnesses.

CHARLES W. KENNEDY.
